UNITED STATES PATENT OFFICE.

WILLIAM J. BERGENS, OF PITTSBURG, PENNSYLVANIA, ASSIGNOR TO NATIONAL VACUUM DEVICES COMPANY, OF PITTSBURG, PENNSYLVANIA, A CORPORATION OF PENNSYLVANIA.

CLEANING DEVICE.

971,518.

Specification of Letters Patent.

Patented Oct. 4, 1910.

Application filed July 13, 1908. Serial No. 443,336.

To all whom it may concern:

Be it known that I, WILLIAM J. BERGENS, a resident of Pittsburgh, in the county of Allegheny and State of Pennsylvania, have 5 invented a new and useful Improvement in Cleaning Devices; and I do hereby declare the following to be a full, clear, and exact description thereof.

My invention relates to cleaning apparatus and more especially to apparatus for use 10 in connection with stables, garages, etc. for the cleaning of horses and vehicles.

The object of my invention is to provide 15 apparatus of this character which may be arranged over-head in such manner as to be out of the way when not in use and so arranged that the flexible hose connection used therewith cannot become entangled with the feet or legs of the horse and so disturb or 20 frighten him.

To these ends my invention comprises, 25 generally stated, a hollow shaft extending down within the compartment from the ceiling, said shaft being connected up with a vacuum cleaning apparatus or with a water supply, a rotary member on said shaft and a counter-balanced arm mounted on said rotary section, a cleaning tool and flexible pipe 30 connections between said tool and said shaft.

Referring to the accompanying drawings 35 Figure 1 is a side view of my improved apparatus; Fig. 2 is an end elevation; and Fig. 3 is an enlarged vertical section of a hollow shaft.

I have illustrated my invention as used in 40 connection with a vacuum cleaning system in which the elbow 2 is connected up by pipe 3 to such a system.

The numeral 4 indicates the ceiling of the 45 stable or other building and secured to said ceiling by means of the bolts 4^a is the section of hollow shafting 5 which is connected to the elbow 2. A hollow shaft section 6 fits up within a seat 7 in the shaft section 5. 50 The shaft section 6 is supported by means of the gland 8. The section 6 has the ring 9 and on each side of said ring are the washers 10. A revolving clamp 11 surrounds the shaft section 6 which is provided with the ball-race 12 to receive the balls 13 which are 55 interposed between said ball-race and the cone 14 on the clamp 11. The clamp 11 has the studs or axles 15 projecting therefrom and mounted on said axles, and secured thereto by the cotter pins 16, is the arm 17.

This arm 17 is bifurcated at 18 and at its inner ends are the weights 19 which act as counter-balances for said arm. The outer end of the arm carries the ring 20. A nipple 21 is provided with the ring 22 and said 60 nipple is secured to the section 6 by means of the coupling 23 secured in place by the set screw 24. A hose or flexible pipe connection 25 is secured to the nipple 21 by means of the hose clamp 26. The hose 25 passes 65 through the ring 20 at the outer end of the arm 17 and secured to the lower end of the hose 25 is a suitable cleaning device 27.

When my improved apparatus is in use in 70 connection with the cleaning of horses the operator simply reaches up and draws down the tool 27 which is suspended at a suitable height and normally held in its raised position by means of the counterbalanced arm 17. By drawing down upon the hose 25 the 75 operator can lower the tool to any desired height and with the horse standing in proper position with reference to the tool the operator can move the tool over the body of the horse, the arm 17 being raised 80 or lowered according to the height at which the tool is being used. Where my improved apparatus is connected up with a vacuum system the dirt, dust or hair brushed from the horse will be drawn in through the tool 85 27 and will be conveyed up through the hose 25 and through the hollow shaft to the pipes of the vacuum cleaning system where it is disposed of in the ordinary manner. In 90 case the horse becomes restive or frightened 95 and it is necessary for the operator to let go of the tool the arm 17 will immediately raise the tool up to a point where it is out of the way and cannot in any way become entangled with the feet or legs of the horse, and just as soon as the cleaning operation 100 is completed the tool, when released, will be automatically drawn up out of the way in position to be readily brought into use when desired for the next cleaning operation.

While I have illustrated my invention as applied to a vacuum system, it is apparent that water might be discharged through the hollow shaft and with a brush of a like character the water will be discharged through the tool 27 and the water will be used to effect the cleaning. Any other suitable tool more adapted for the specific purpose for which it is to be used might be secured to 110

the hose and I do not confine myself to any particular class of work to which my invention may be applied.

What I claim is:

5 1. In a cleaning device, the combination with an overhead support, of a hollow shaft extending down therefrom, a pipe connected to the upper end of said hollow shaft, a rotary sleeve on said shaft, a counterbalanced arm mounted on said rotary sleeve, a cleaning tool and flexible connections between said tool and said shaft and supported by said counterbalanced arm.

15 2. In a cleaning device, the combination with a suitable overhead support, a hollow shaft extending down therefrom, a pipe connected to the upper end of said hollow shaft, a second hollow shaft extending up within the lower end of said first named shaft and supported therefrom, a rotary sleeve on said second named shaft, a counterbalanced arm mounted on said rotary sleeve, a cleaning tool, flexible connections between said tool and said shaft, and supported by said 25 counterbalanced arm.

3. In a cleaning device the combination with a suitable overhead support, a hollow shaft extending down therefrom, a pipe

connected to the upper end of said hollow shaft, a second hollow shaft extending up 30 within the lower end of said first named shaft, and supported therefrom, a rotary sleeve on said second shaft, a ball race on said second named shaft, balls interposed between said ball race and said sleeve, a 35 counterbalanced arm mounted on said sleeve, a cleaning tool, and flexible connections between said tool and said shaft and supported by said counterbalanced arm.

4. In a cleaning device, the combination 40 with a suitable overhead support, a hollow shaft extending down therefrom, a pipe connected up to the upper end of said hollow shaft, a rotary sleeve on said shaft, a counterbalanced arm on said rotary sleeve, 45 a cleaning tool, a flexible pipe, connections between said flexible pipe and said shaft, and a ring at the outer end of said arm through which said flexible pipe passes.

In testimony whereof, I, the said WILLIAM 50 J. BERGENS have hereunto set my hand.

WILLIAM J. BERGENS.
